(57) **CLAIM**

The ornamental design for a combination boot jack, boot tray and boot rack, as shown and described.

DESCRIPTION

FIG. 1 is a front perspective view showing the new design; FIG. 2 is a rear perspective view thereof;

FIG. 3 is a top view thereof;

FIG. 4 is a bottom view thereof;

FIG. 5 is a rear view thereof;

FIG. 6 is a front view thereof;

FIG. 7 is a right side view thereof;

FIG. 8 is a left side view thereof; and,

FIG. 9 is a front perspective view thereof.

In the drawings, the broken lines depict a pair of boots and square pads, which form no part of the claim.
